MAGNETIC TAPE CARTRIDGE

Anthony Gelardi, Cranston, R.I., and Gregory Mathus,
Cambridge, Mass., assignors, to The Morningstar
Corporation, Cambridge, Mass., a corporation of
Massachusetts

Filed Nov. 15, 1967, Ser. No. 9,429

Term of patent 14 years

(Cl. D26—14)

FIG. 2

FIG. 1

FIG. 4

FIG. 3

FIG. 5

FIG. 6

FIG. 7

FIG. 1 is a top plan view of the magnetic tape cartridge;

FIG. 2 is a rear elevation view thereof;

FIG. 3 is a front elevation view thereof;

FIG. 4 is a side elevation view thereof;

FIG. 5 is a cross sectional view of the magnetic tape cartridge taken along the section line 5-5 in FIG. 2;

FIG. 6 is a top view of another embodiment of magnetic tape cartridge; and

FIG. 7 is a bottom plan view of the magnetic tape cartridge shown in each of the embodiments of FIGS. 1-5 and FIG. 6.

The dominant feature of the design resides in the portions shown in full lines.

We claim:

The ornamental design for a magnetic tape cartridge, as shown and described.
